United States Patent Office

Des. 218,764
Patented Sept. 22, 1970

218,764

GAME TARGET

Adolph Abraham, 1357 Barry Ave., Chicago, Ill.

Filed Apr. 14, 1969, Ser. No. 16,745

Term of patent 14 years

Int. Cl. D21—01

U.S. Cl. D34—5

FIG. 1

FIG. 2

FIG. 3

FIG. 4

FIG. 1 is a perspective view of a game target embodying my new design;

FIG. 2 is a side elevational view thereof;

FIG. 3 is a front elevational view of the game target; and

FIG. 4 is a top plan view of the game target.

I claim:

The ornamental design for a game target, substantially as shown.
